UNITED STATES PATENT OFFICE.

JOHN A. BEACH, OF MUSKEGON, MICHIGAN.

LAY-OUT TOOL.

1,298,866.

Specification of Letters Patent.

Patented Apr. 1, 1919.

Application filed November 4, 1918. Serial No. 280,923.

To all whom it may concern:

Be it known that I, JOHN A. BEACH, a citizen of the United States, residing at Muskegon, county of Muskegon, State of Michigan, have invented certain new and useful Improvements in Lay-Out Tools, of which the following is a specification.

This invention relates to improvements in layout tools.

10 The main objects of this invention are:

First, to provide an improved combination layout tool and center punch which is easily and quickly adapted or adjusted and manipulated for the laying out of different 15 kinds of work, such as flat and round work.

Second, to provide an improved punch head for lay out work and center punch work adapted for use with combination sets such as scale and square heads or scale and center 20 heads.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated in 30 the accompanying drawing, forming a part of this specification, in which:

Figure I is a detail side view of my improved lay out tool showing one manner of using the same.

35 Fig. II is a detail vertical section on a line corresponding to line 2—2 of Fig. III, through the punch head, the scale and punch being shown in full lines.

Fig. III is a transverse section on a line 40 corresponding to line 3—3 of Figs. I and II.

Fig. IV is a detail view of my improved layout tool adapted as a center punch, a shaft being indicated by dotted lines.

Fig. V is an end view of the punch head 45 mounted upon a scale as in the adaptation shown in Fig. IV.

Fig. VI is a detail side elevation looking from the left of Fig. V.

In the drawing similar reference characters 50 refer to similar parts throughout the several views, and the sectional views are taken looking in the direction of the little arrows at the ends of the section lines.

Referring to the drawing, 1 represents the

work, 2 the scale, and 3 a square head adjustably mounted upon the scale, the scale being provided with a longitudinal groove 4 and the square head with a clamping means 5 by which the square head is adjustably and removably secured to the scale. These parts 60 are of well known construction and therefore are not illustrated with further detail.

I provide a punch head 6 having a vertical bore 7 for the punch 8, the head being slotted at 9 to receive the pin 10 which retains the punch. The coiled spring 11 normally retracts the punch.

The punch head 6 is provided with a vertical slot-like scale socket 12. The center plane of the socket is in an axial plane or a central plane through the punch, the inner end of the socket being at the periphery of the punch. In the structure illustrated the radius of the punch is equal to one or more units of the scale—one eighth of an inch, 75 and in laying out the work the user takes this into consideration.

The punch head is provided with a rectangular scale seat 13 in its bottom adapted to receive the scale as shown in Fig. IV. The longitudinal edge of this seat 13 is in the same plane as the center plane of the socket and the angle of the seat is at the periphery of the punch, as clearly shown in Fig. IV, the inner end of the socket and this angle coinciding, as do also the longitudinal edge of the seat and the center plane of the socket.

When used as a center punch the center head 14 is mounted upon the scale, the heads 3 and 14 being interchangeable and adjustable. The scale is retained in the socket by means of the opposed set screws 15, while it is retained in the seat 13 by means of the clamp 16, which is removably arranged in the hole 17 transversely through the head, 90 the clamp being provided with a clamping nut 18. When this nut is removed the clamp can be withdrawn or inserted.

My improved layout tool enables the accurate and rapid laying out of flat or round work. I have shown the scale and the square and center heads mainly in conventional form and my improvements may be readily adapted to various so-called combination sets which are now in use.

I have illustrated and described my improvements in an adaptation which I find very practical and satisfactory. I have not

attempted to illustrate or describe other embodiments or adaptations which I contemplate as I believe the disclosure made will enable those skilled in the art to which my invention relates to embody or adapt the same as may be desired.

Having thus described my invention, what I claim as new and desire to secure by Letters Patent, is:

- 10 1. The combination with a scale and square and center heads adapted to be interchangeably and adjustably associated with said scale, of a punch head provided with a punch and having a vertical scale socket and 15 a horizontal rectangular scale seat having a longitudinal edge, the center plane of the socket and the longitudinal edge of the seat being in the same plane and radial to said punch, a removable clamp for securing said 20 scale in said seat, and clamping screws for securing said scale in said socket.
2. The combination with a scale, of a punch head provided with a punch and having a vertical scale socket and a horizontal 25 rectangular scale seat having a longitudinal edge, the center plane of the socket and the longitudinal edge of the seat being in the same plane and radial to said punch, a removable clamp for securing said scale in 30 said seat, and clamping screws for securing said scale in said socket.
3. The combination with a scale, of a punch head provided with a punch and having a vertical scale socket and a horizontal 35 rectangular scale seat having a longitudinal edge, the center plane of the socket and the longitudinal edge of the seat being in the same plane and radial to said punch, the inner end of the socket and the angle of 40 said seat being at the periphery of the punch, the radius of the punch being equal to a unit of the scale, a removable clamp for

securing said scale in said seat, and clamping screws for securing said scale in said socket.

4. The combination with a scale and a square head adjustably associated with said scale, of a punch head provided with a punch and having a vertical scale socket, the center plane of the socket being radial to said punch, and means for securing said scale in said socket.

5. The combination with a scale, of a punch head provided with a punch and having a vertical scale socket, the center plane 55 of the socket being radial to said punch, and means for securing said scale in said socket with the longitudinal edge of the scale at right angles to the axis of the punch.

6. The combination with a scale, of a punch head provided with a punch and having a vertical scale socket, the center plane 60 of the socket being radial to said punch, the inner end of the socket being at the periphery of the punch, the radius of the punch being equal to a unit of the scale, and means for securing said scale in said socket.

7. The combination with a scale, of a punch head provided with a punch and having a horizontal rectangular scale seat having a longitudinal edge in a plane radial to 65 said punch, the inner angle of said seat being at the periphery of the punch, the radius of the punch being equal to a unit 70 of the scale, and a means for securing said scale in said seat.

In witness whereof, I have hereunto set my hand and seal in the presence of two witnesses.

JOHN A. BEACH. [L.S.]
